GLARE SHIELD

Filed Aug. 19, 1929

UNITED STATES PATENT OFFICE

LONGWORTH B. LEWIS, OF MONTROSS, VIRGINIA

GLARE SHIELD

Application filed August 19, 1929. Serial No. 386,887.

This invention relates to anti-glare shields for motor vehicles and more particularly to a device of this character having means for electrically controlling the same.

The principal object of this invention is to provide a glare shield operated by a single means whereby the shield will be folded away from the line of vision of the driver and into the line of vision when so desired. At the present time there are many anti-glare devices but none so far as I know, which utilize the same means for automatically swinging the anti-glare device out of operative position, as used to swing the same into operative position. The means for carrying this out should be placed at a readily accessible point so that the driver need not change his position at the wheel, nor move his hands from the near vicinity of the wheel or steering column.

Another object is to provide means for operating the anti-glare device without diverting the driver from his task of operating the car.

Other objects will be disclosed in the specification and drawings, which are made a part of this application.

In the drawings—

Fig. 1 is an elevation illustrating the use of my device as attached to an automobile;

Fig. 2 is a front elevation, partly in section, of my device in shielding position;

Fig. 3 is a horizontal section on the line 3—3 of Fig. 2;

Fig. 4 is an end elevation partly in section, showing the shield in partly raised position;

Fig. 5 is a vertical section taken intermediate the device and showing the device in raised inoperative position;

Fig. 6 is a similar view taken adjacent the locking ratchet to illustrate the normal locked position of the device;

Fig. 7 is a vertical section on line 7—7 of Fig. 2 through the hinge rod showing the lost motion means which permits the successive raising operation of the device;

Figs. 8, 9 and 10 are similar views taken on line 8—8, 9—9, and 10—10 of Fig. 2, showing positions in the raising of the device to an inoperative position; and

Fig. 11 is a wiring diagram showing how the device may be hooked up to the battery of a vehicle and showing two switches, one of which controls the five large magnets which operate to raise the device to a horizontal position.

Referring to the drawings, in which like parts are designated with similar numerals, numeral 1 designates an anti-glare device having a frame 2, containing amber or colored glass 3. Extending through the upper portion 4 of frame 2 is a hinge pin 5. The frame 2 is adapted to pivotally swing from the hood 6, the hood thus being attached above a windshield 7 in proper position. The ends 8 of said hinge pin 5 are preferably squared, to be received in square bearing openings 9, in ears 10 which are fixed to the rear of the glare shield frame 2 in order that the turning of the pin 5 may in turn operate the frame 2. The hinge pin 5 has mounted thereon at spaced intervals, radially extending arms 11 with contact spring members 12 fixed to the ends of said arms 11. The radial arms 11 are spaced a predetermined distance apart for the purpose of raising the shield 1 from a vertical operative position to a horizontal inoperative position. A plurality of magnets 13, are mounted in the hood 6, in position to attract the radial contact members 12 in succession so that the shield 1 is electrically and automatically raised from a vertical position in a series of movements. The radial arms 11 are provided with pins 14 to slide in spaced slots 15 cut into the hinge pin 5 so that the proper lost motion is provided to permit the successive movements of the radial arms 11. A pawl 16 and ratchet 17, mounted on the hinge pin 5, lock the shield 1 in an inoperative position; the pawl 16 being forced into engagement with the ratchet 17 by a spring 18. A magnet 19, placed adjacent the pawl 16 will retract the said pawl 16 and free the ratchet 17, upon being energized. A switch 20, of the progressive type, is mounted on steering wheel 21. The progressive switch 20 has a terminal 22, which is connected up with the magnet 19, which controls the pawl 16 and ratchet 17.

and a second terminal 23, placed beyond the terminal 22, which controls five large magnets 13, which attract the radial arms 11.

As actually operated, the switch 20 will be pressed until it contacts with terminal 23, thus closing the circuit and energizing the five large magnets 13. The radial arms 11, five in number, are arranged in a fan-shape so that the arm nearest perpendicular will be directly opposite an energized magnet. If I divide the 90° of the distance which represents the distance from the horizontal position of the shield 1, to the perpendicular position, by 5, I find that there will be 18° between each radial arm 11 and 18° between the uppermost arm 11 and the magnets 13. The magnet opposite the uppermost arm is strong enough to attract the uppermost arm, but the adjacent magnet is not strong enough to attract the arm adjacent to the uppermost radial arm, it being 36° from the magnet instead of 18°, and the same applies to the other radial arms, which are beyond the 18°. Since each of the radial arms are keyed on to the hinge pin 5, with provision for lost motion, with the exception of one arm, which is furthest disposed from the magnets 13, there being no need for lost motion in this instance, the radial arm nearest the upright position will be attracted by the magnet opposite thereto and in turn will revolve each of the radial arms through a corresponding distance of 18°. As soon as the next uppermost arm reaches the position 18° from the magnet oppositely disposed to it, the movement will be continued and each arm will be revolved through a second 18°, movement being continued until each radial arm contacts with its corresponding magnet and the shield 1 has been raised from a perpendicular, operative position, to a horizontal inoperative position. The release of the switch 20 serves to lock the shield 1 in a horizontal position. When the driver desires to lower the shield to a perpendicular operative position, the switch 20 is depressed slightly until it contacts with the terminal 22, which only serves to energize the magnet 19. Upon the magnet 19 being energized the pawl 16 will be disconnected from the ratchet 17 and since the magnets 13 are no longer energized, the shield 1 will fall of its own weight to a perpendicular operative position, the radial arms 11 seeking the fan-shaped position to the 90° above described, and the fall of the shield being retarded by a spring pawl 24 acting on a serrated hub of the ratchet 17.

It is obvious that a simple, economical, automatically, electrically operated glare shield has been provided, which is controlled from a single switch on a steering wheel and that may be operated without in any way interfering with the driver's operation of a car.

What is claimed is:

1. In an anti-glare device, a shield pivotally associated with a vehicle, a series of electrical magnets adjacent said shield, a plurality of contact members secured to said shield, means for locking the shield in inoperative position and common means for energizing said magnets to raise the shield into inoperative position and for releasing said locking means in predetermined sequence. 70

2. In an anti-glare device, a shield pivotally associated with a vehicle, a series of magnets adjacent said shield, a plurality of radial arms extending from said shield, said radial arms spaced equal distance from each other and varying distances from said shield, means for locking the shield in inoperative position and common electrical means for energizing said magnets to raise said shield into inoperative position and for releasing said locking means in predetermined sequence. 75 80 85

3. In an anti-glare device, a shield pivotally associated with a vehicle, means for raising the shield in inoperative position, a ratchet and pawl for locking the shield in inoperative position, a magnet for withdrawing the pawl from engagement with said ratchet and common means for operating said raising means and withdrawing said pawl from said ratchet in predetermined sequence. 90 95

4. In an anti-glare device, a shield pivotally associated with a vehicle, a series of electrical magnets adjacent said shield, a plurality of radial arms extending from said shield, said radial arms spaced from each other and positioned opposite one of said magnets, said arms extending varying distances from said shield and said magnets, a ratchet and pawl for engaging said ratchet to lock said shield in inoperative position, an electric magnet to withdraw said pawl when energized, and common means for energizing said series of magnets to raise said shield into inoperative position and to withdraw said pawl from engagement with said ratchet in predetermined sequence. 100 105 110

5. In an anti-glare device, a shield adapted to swing on an axis; a shaft, armatures connected to the shaft, and angularly spaced apart; a magnet opposite each armature; and a circuit for energizing the magnets to gather in the armatures in succession. 115

6. In an anti-glare device, a shield mounted on a shaft; armatures pivoted along the shaft; angularly spaced apart; a pulling magnet opposite each armature; a ratchet attached to the shaft; a pawl adapted to engage the ratchet, having a withdrawing magnet; and a progressive switch having the withdrawing magnet in one circuit and the pulling magnets in another circuit. 120 125

In testimony whereof I affix my signature.
